UNITED STATES PATENT OFFICE.

PETER J. GORDON, OF NEW YORK, N. Y., ASSIGNOR TO H. A. CARY COMPANY, OF SAME PLACE.

DESIGN FOR A SILVERSMITH'S STOCK.

SPECIFICATION forming part of Design No. 35,058, dated September 10, 1901.

Application filed August 17, 1901. Serial No. 72,454. Term of patent 3½ years.

To all whom it may concern:

Be it known that I, PETER J. GORDON, a citizen of the United States, and a resident of the city of New York, borough of Manhattan, in 5 the county and State of New York, have invented and produced a new and original Design for Silversmiths' Stock, of which the following is a full, clear, and exact description, reference being had to the accompanying drawing, forming a part thereof, in which is shown a plan view of a sample of silversmiths' stock embodying the features of my design.

The leading features of the design consist in a scroll and in the representation of floral 5 snow-balls pendent from the scroll.

The minor features of the design consist in

the rococo character of the scroll and in the association with the floral snow-balls of foliage and in the stems of the snow-balls leading into portions of the scroll. 20

Having thus described my invention, I claim as new and desire to secure by Letters Patent—

The design for silversmiths' stock herein shown and described. 25

In testimony whereof I have signed my name to this specification in the presence of two subscribing witnesses.

PETER J. GORDON.
